UNITED STATES PATENT OFFICE.

WILLIAM E. HALES, OF DETROIT, MICHIGAN, ASSIGNOR OF TWO-THIRDS TO ARZA PORTER AND WILLIAM J. WEAVER, BOTH OF DETROIT, MICHIGAN.

VENDING-MACHINE.

961,694.

Specification of Letters Patent. Patented June 14, 1910.

Application filed July 12, 1909. Serial No. 507,045.

To all whom it may concern:

Be it known that I, WILLIAM E. HALES, citizen of the United States, residing at Detroit, county of Wayne, State of Michigan, have invented a certain new and useful Improvement in Vending-Machines, and declare the following to be a full, clear, and exact description of the same, such as will enable others skilled in the art to which it pertains to make and use the same, reference being had to the accompanying drawings, which form a part of this specification.

This invention relates to vending machines.

It has for its object an improved coin controlled vending machine, especially adapted for the exposure and sale of cigars from the original boxes or packages in which cigars are sold.

In the drawings:—Figure 1, is a sectional elevation of the vending machine. Fig. 2, is a detail of part of the expelling mechanism. Fig. 3, is a horizontal section at the line *a—a* of Fig. 1. Fig. 4, is a sectional plan on an enlarged scale of the delivery box, looking in the direction of the arrow with the plates 39 and 20 removed. Fig. 5, is a side elevation of the internal mechanism from the coin chute. Fig. 6, is a side elevation of mechanism in the same coin chute. The two views of Figs. 5 and 6 are shown on opposite sides. The cover or casing is removed in both views. Fig. 7, is a detail of one-half of the box holder. Fig. 8, is a detail of the final expelling mechanism. Fig. 9, is a perspective of the locating ring used to finally locate the turret in which the boxes of cigars are stored.

The cigars are packed in boxes 1, which are stored in a rotatable, prismatic turret mounted on a central post 2 that rises from a stationary base 3. The turret is provided with a floor 4, and there are openings 6 through the floor opposite each face of the turret. The openings are of a size to allow the cigars to drop from the box through the floor into a passage 7, through which they are forced in definite numbers to the outside of the case. There are two impulses required to transfer a cigar from the box to the pocket outside the turret. The box 1, with one end removed therefrom, is placed with its open top against the glazed side 8 of the turret, and with its open end arranged

for the exit of the cigars therefrom over the 55 opening 6 through the bottom 4 of the turret. The box is held in place by springs 10 that engage against the sides of the box, and a spring 11 that engages against the bottom, which is now in vertical position, and is 60 turned toward the post 2. The cigars drop from the box into the passage 7 in front of a plunger 12 that, for purposes of lightness, is preferably made hollow, and is made of a vertical thickness to correspond with a single cigar, and with horizontal breadth to correspond with the depth of the cigar box to which the machine is adapted.

The expelling plunger 12 is pushed outward across the vertical part of the conduit 70 or passage 7 under the end of the box by lengthwise movement of the rod 29 and pushes whatever cigars may be lying on the vertical part of the conduit out through the side opening 13, where they roll or drop by 75 gravity down a short inclined passage 14 that is a continuation of the conduit, against a stop 15, leaving a definite number of cigars under an overhanging guard 17. On the return of rod 29 a trip pawl 40 mounted thereon actuates lifting fingers 18, which now lift a definite number of cigars from off the inclined head of the passage or conduit 7 over the stop 15, and through an aperture in the wall of the conduit 19 down which the cigars 80 travel, and come to rest in a pocket 20 from which they may be removed manually, and over which extends a guard plate 39. On the opposite or right-hand side the box-supporting springs and the conduit members 85 90 are similarly shown, but the box and the various movable members of the mechanism are omitted.

An understanding of the details of the mechanism will require an explanation first 95 of the expelling mechanism, which has already been briefly referred to, and next of the means for actuating the expelling mechanism, which is coin-controlled and partially coin-actuated, the coin being required to 100 intervene between movable parts of the mechanism in order that the primary actuating lever may complete the chain of movements which result in expelling the cigars.

The turret is rotated manually, and may 105 be rotated at any time, whether there is a coin in the coin passage-way or not, and it is therefore possible to turn the turret to

select any one of the several varieties of cigars which are exposed for sale therein, since it is possible to expose a different brand of cigars opposite each one of the 5 faces of the turret. The primary actuating lever 21, (which is pivoted at 21^a to the vertically supported plate 70) when a coin has been interposed in the coin receptacle 22, actuates the rod 23 through the medium 10 of the pin 21^b and lever 59, and pushes it inward toward the central post 2 of the machine; this movement places under tension a spring 24 which returns the rod 23 to its normal position as soon as it is released. The rod 23, cannot, however, be pushed inward unless the turret has been brought to rest with a ring 25 from the bottom in proper position to allow one of the 15 several notches 26 on this ring to register 20 with the pin 27 on the rod 23. When the ring is in position for this registration, the turret is in position to properly drop a cigar from one of the conduits or boxes through the opening in the floor of the turret, and if 25 the turret is not brought to the proper position for this the machine cannot be worked at all. When the rod 23 is pushed inward in the way described, it actuates an angle lever 28 pivoted to the base, and this in 30 turn actuates an expelling rod 29. The rod 29 carries a post 30 on the top of which is a pawl or catch 31, and this pawl or catch 31 at times engages with the expelling plunger 12, and at times passes without engaging 35 the expelling plunger 12. If there be on the inclined continuation of the conduit 14 a cigar or cigars, the expelling plunger 12 is not actuated. If the inclined part of the conduit is empty, then the expelling 40 plunger 12 is actuated. If there are cigars on the incline, they rest primarily on the outer end 16 of a short lever, the inner end 34 of which otherwise hangs in front of a rod 33 that passes under or through the 45 lower part of the expelling plunger; and their weight resting on the outer end of the lever causes the inner end of the lever to rise above the path of the rod 33 and leaves the rod 33 free to move forward. 50 On the under side of the rod 33 is a feather 35, which engages through a notch in the pawl 31, and allows the pawl 31 to travel with the rod 29 and slide along the under edge of the feather with the forward notched 55 end of the pawl 31 held down in position shown by Fig. 1, throughout the period of its travel; when this condition exists the two rods 29 and 35 travel together because the resistance to the expelling plunger 12 is 60 greater than the resistance to the rod 33. If, however, there is no weight on the lever end 16, the rod 33 is engaged by the lever 34, the rear end of the pawl 31 which is not cleft engages under the feather 35 and lifts 65 the forward or cleft end upward, and brings

it into engagement with the expelling plunger 12, and forces it forward through the bottom end of the conduit and forces a layer of cigars from the box into the inclined part of the continuation 14 of the conduit. 70

The forward end of the rod 29 is broadened and flattened, and on the broad part is a pawl 40 held in place by a spring 41 against the pin 42, and adapted to engage a hanger 43 on the shaft of fingers 18 which 75 acts as a rock arm on rock shaft 44 of the said fingers. The pawl 40 passes the hanger 43 on the outward movement, and engages it on the return movement, when the rod is brought back to its normal position by 80 force of the springs 46 and 47. The rod 33 is brought back to its normal position by finger 48, which engages against a collar 50 on the rod. The fingers 18 swing through notches 58 in the incline 14 and stop 15. 85

In Figs. 5 and 6 the frame plate and included mechanism only is shown; the frame here consists of a plate 70 with levers on each side of the frame, and with parts that reach through the plate to perform 90 their functions; for convenience I will call the side along which the coin travels the front, and the opposite side the rear; on the front is a coin chute between overhanging guides 71 and 72 that are secured to the 95 frame plate. Below the chute and parallel with it is a rock shaft 52 mounted in bearings 53 and 54; at the top end the rock shaft carries a rock arm 51, and at the end of the arm is a pin 50 that normally reaches across 100 the chute and acts as a stop for the coin 80; at the bottom end the shaft is provided with a second arm that reaches through the frame plate 70 into the path of an arm 61 of the lever 59; on the lower end of the shaft 52 is 105 a coin dropper 64 which is provided with a turned or thickened edge 164; the coin comes to rest in front of this dropper with the lower edge still engaged behind the lower guide 72 and the upper edge of the coin engaged against a stop 73. The dropper has a corner cut away so that it can swing by the stop 73; the dropper is held against a finger 74 by a spring 75. A finger 76 mounted on rod 23 presses the dropper over until 110 the coin is disengaged from stop 73, when it drops by gravity. The lever 21 is pivoted to the plate 70 on the front side thereof and is provided with a rock arm 56 and ratchet 57 with which engages a "complete throw 115 pawl" 67; to an arm of the lever 21 is pivoted a lever 59, which is on the rear face of the plate 70, with the connecting pin between the two engaging through a slot 96; the upper end of the lever 59 is provided 120 with a pin 60 that engages behind a coin 80; this pin reaches through a slot in the plate; the lower end of the lever engages with and actuates the rod 24 with which it has a pin and slot connection; an arm 61 125

extends from the lower end forward and engages with and actuates the rock arm 62 on the rock shaft 52.

What I claim is:—

5 1. In a vending machine, in combination with a storage casing wherein a quantity of articles to be vended may be stored, said casing being apertured for delivery purposes at the bottom, a horizontally movable member 10 normally out of engagement with the casing and its contents, means whereby said member may be actuated against the lowermost of the stored articles to effect their displacement from the storage casing, a 15 holding trough into which the articles fall when first displaced, and a lifting member adapted to be actuated by the return movement of said horizontally movable member, whereby the displaced articles are expelled 20 from said holding trough, substantially as described.

2. A vending machine having in combination with a storage casing, horizontally movable means for forcing a predetermined number of the articles stored therein into the 25 delivery portion thereof, means actuated by the movement of said last-mentioned means

for completing the ejection of the articles from the casing, and manually actuatable means for imparting a movement to the delivery mechanism, substantially as described. 30

3. In combination with a casing wherein various classes of articles may be accessibly stored separate from one another, a horizontally reciprocatory member adapted to 35 force a predetermined number of articles of the class selected from their previous place of storage, a holding trough into which the articles fall when thus displaced, means for preventing the engagement of said reciprocatory member against said articles unless said member and the casing are in proper relative position, and means actuated by the return movement of the reciprocating member 40 for effecting the displacement and delivery of the articles deposited in the holding trough, substantially as described. 45

In testimony whereof, I sign this specification in the presence of two witnesses.
